UNITED STATES PATENT OFFICE.

AUGUSTUS F. PRIEST, OF OAK PARK, ILLINOIS.

RESILIENT HEEL AND THE LIKE.

1,231,296.

Specification of Letters Patent. Patented June 26, 1917.

Application filed April 11, 1917. Serial No. 161,113.

To all whom it may concern:

Be it known that I, AUGUSTUS F. PRIEST, a citizen of the United States, residing at Oak Park, in the county of Cook and State 5 of Illinois, have invented certain new and useful Improvements in Resilient Heels and the like, of which the following is a specification.

My invention pertains to features of novelty and improvement in rubber or similar 10 resilient cushions, such as shoe heels, soles, and the like, and door-mats, floor-coverings, and appliances of that general style.

Its prime or leading object is to provide a 15 structure of this character which will have greater elasticity than the appliances now on the market and yet wear with economy and prevent slipping. When the invention is embodied in a rubber heel, for example, 20 the bottom face thereof is provided with an elevated or raised portion or suction structure intended to engage the sidewalk or floor in such a way as to prevent slipping or sliding, and, to bring this about to the best 25 advantage, that part of the heel in register with the raised boss or suction cup part has an air-cushion to make such portion of the structure more resilient, whereby to facilitate the action of the suction cup and in- 30 crease the elasticity or cushioning effect of the heel.

In order that those skilled in this art may have a full and complete understanding of this invention and its various advantages, I 35 have illustrated a preferred embodiment of the same in the accompanying drawing forming a part of this specification and throughout the various views of which like reference characters refer to the same parts.

40 In the drawing:

Figure 1 is a face or top view of a rubber-heel embodying the invention;

Fig. 2 is a cross-section on line 2—2 of Fig. 1, and

45 Fig. 3 is a bottom view of the heel.

Referring to the drawing, it will be observed that the rubber heel 10 is of the usual contour and customary thickness, being provided with a plurality of counter- 50 sunk holes 11 for the accommodation of any suitable means, such as nails, for fastening the heel to the shoe. The middle portion of the bottom face of the heel has an elevation or circular boss 12, extended downwardly 55 when the heel is on the shoe, and equipped

with an annular or ring groove 13, such recessed projection constituting the suction cup element. In order to make this part of the heel more resilient or elastic, and to render the suction cup more effective in action, that is, to facilitate the initial gripping of the pavement and to aid in its release, which, of course, as will be readily understood, alternately occurs in rather rapid succession during the walking of the individual wearing the shoes provided with such heels, the other side of the heel has a depression 14 forming an elastic air cushion. Such cushion increases the resiliency of the heel as a whole and permits a more ready depression or compression of the grooved boss as the wearer progressively brings down the heel in the act of walking; it reduces the amount of wear on such raised central portion of the heel; and it aids in breaking the suction grip on the pavement or floor as the wearer lifts the heel. Due to the gradual compression of the air in the cushion and the bending or flexure of the rubber over and around the cushion, the heel as a whole is 80 more resilient and has more cushioning effect regardless of whether the boss is provided with the suction groove or not.

The number, shape, and location of the air cushions and suction cups is more or less 85 immaterial, as is also the exact disposition and character of the means for rendering more elastic, pliable, or compressible, that part of the heel provided with the boss.

In case the invention is used in connection with a shoe sole or floor-mat, or similar appliance, the number of cushioned projections or suction cups would ordinarily, but not necessarily, be increased to advantage.

The invention, as will be readily understood by those skilled in this art, is not limited and restricted to the precise and exact details of structure presented herewith, because these may be varied within comparatively wide limits without departure from 100 the heart and substance of the invention and without the sacrifice of any of its substantial benefits and advantages.

I claim:

1. A cushion appliance of the character 105 described adapted for use in connection with shoes and the like, comprising a resilient body equipped with a portion raised above the main body and recessed to provide a suction cup, said body at the suction cup por- 110

tion being formed to provide increased resiliency, whereby to increase the cushioning effect of the appliance and facilitate the action of the suction cup, substantially as 5 described.

2. A cushion appliance of the character described adapted for use in connection with shoes and the like, comprising a resilient body equipped with a portion raised above 10 the main body and recessed to provide a suction cup, said body being recessed beneath said raised portion to provide an air cushion whereby to increase the cushioning effect of the appliance and facilitate the

action of the suction cup, substantially as 15 described.

3. A cushion appliance of the character described, adapted for use in connection with shoes and the like, comprising a resilient body equipped with a portion raised above 20 the main body and grooved to provide a suction cup and a central boss, said body being recessed beneath said raised portion to provide an air cushion whereby to increase the cushioning effect of the appliance 25 and to facilitate the action of the suction cup, substantially as described.

AUGUSTUS F. PRIEST.
